UNITED STATES PATENT OFFICE.

RUSSELL E. BENNER, OF DETROIT, MICHIGAN, ASSIGNOR TO BURROUGHS ADDING MACHINE COMPANY, OF DETROIT, MICHIGAN, A CORPORATION OF MICHIGAN.

AUTOMATIC INK-RIBBON-REVERSING MECHANISM.

941,554.

Specification of Letters Patent. Patented Nov. 30, 1909.

Application filed April 6, 1908. Serial No. 425,471.

To all whom it may concern:

Be it known that I, RUSSELL E. BENNER, a citizen of the United States, residing at Detroit, in the county of Wayne and State of Michigan, have invented certain new and useful Improvements in Automatic Ink-Ribbon-Reversing Mechanism, of which the following is a specification.

The present invention relates to mechanism for use in adding machines or other machines which employ an ink ribbon for printing purposes, which mechanism provides for automatically reversing the direction in which such ribbon travels step by step as the machine is operated.

One object of the present invention is to provide a form of mechanism which will provide for the reversal taking place without imposing any strain upon the ribbon.

Thus with a ratchet and pawl feed mechanism the reversal will take place when the feeding pawl is being retracted.

Another object of the invention is to provide a construction in which the taking effect of feed reversing devices as a result of diminution of the supply of ribbon on the unwinding spool will not rely upon support afforded by the ribbon alone as to the timing of the reversal. Thus where the ribbon spools have depressions into which certain parts controlling the reversing devices are adapted to enter, the exclusion of such parts will not be effected simply by reason of the ribbon itself overlying the openings but rigid coverings will be provided for such openings so that the controlling parts cannot take effect to produce a reversal in the feed until the ribbon is entirely unwound from one spool, such reversal being exactly timed in this connection and not likely to vary by reason of the ribbon yielding more or less where bridging an opening in the spool.

With these and incidental objects in view the invention consists in certain novel features of construction and combinations of parts, the essential elements whereof are recited in the appended claims and a preferred form of embodiment of which is illustrated in the accompanying drawings and described in detail hereinafter.

Of said drawings Figure 1 represents a top plan view of mechanism embodying the invention as applied to a machine on which printing or type-writing is done on the so-

called "front strike" order; Fig. 2 is a front elevation of the same; Fig. 3 is an axial section of parts at the right of Figs. 1 and 2; Fig. 4 is a cross-section on line 4—4 of Fig. 2 with all but a fragment of the ratchet wheel omitted and the ribbon spool unwound; Fig. 4^a is a section on line 4^a—4^a of Fig. 4 on an enlarged scale; Fig. 5 is a detail perspective view of a guard plate such as carried by the ink-ribbon; Fig. 6 is a right-side elevation with parts broken away and in section so that the view resembles Fig. 4, though a different relative positioning of parts is shown as the ribbon spool is not entirely unwound; Fig. 7 is a left-side elevation similar to the right-side elevation in Fig. 6, with the ribbon represented as largely wound upon the spool; Fig. 8 is an outer side view of one of the spools; Figs. 9 and 10 are perspective details of the right-hand feed pawl controller and feed pawl respectively; and Figs. 11 and 12 are similar views of the left-hand feed pawl and its controller respectively.

The appliance may be used in various connections, as in typewriting machines and adding and listing machines, and for the purpose of the present specification may be considered as mounted upon the frame-work 7 of an adding machine employing a roller platen 17 and designed to print with a "front strike". So the ink-ribbon *x* extends across in front of the platen between suitable guiding brackets 7^a secured to the frame-work 7 and shaped to properly conduct the ribbon to and from the spools which stand at right angles to the platen and turn on studs 70 secured in and projecting outwardly from the side-pieces of the frame-work respectively.

Passing now to the means for alternately turning the spools, on said studs 70 are journaled a pair of bell-crank levers, the rearwardly and upwardly projecting arms 70^a of which have jointed to them respectively links 70^b extending downwardly and rearwardly and jointed at the rear ends to crank arms on a rock shaft 70^c, one of said crank arms 70^c appearing in Fig. 6. Said rock shaft is oscillated in every operation of the machine through any suitable connections and will rock the bell cranks back and forth on the shafts 70. The forwardly extending arms 70^a of said bell cranks carry a rock rod 70^d journaled in suitable bearings 100

on said arms. On said rod are loosely mounted the pawls 71 and 72 which actuate the ribbon-winding ratchet wheels 71^a and 72^a. These ratchet wheels are loosely mounted upon the long pivot studs 70 and the ribbon spools 71^b and 72^b are also loosely mounted upon said studs being removable endwise therefrom and adapted to be engaged with the ratchet wheels for rotation thereby,—as for example, through the medium of a pin *a* secured in the ratchet and a socket *b* in the spool (Fig. 3).

The pawl 71 extends downward from the rock rod 70^c, whereas the pawl 72 extends upward from said rod, and controlling devices for the pawls are correspondingly arranged, such controlling devices, however, being secured to the rod. Thus rocking of the rod in one direction will disengage one pawl from its ratchet wheel and engage the other pawl with its ratchet wheel, and vice versa. The controlling devices referred to are in the form of arms 71^c and 72^c secured to the rod and formed with laterally turned lips 71^d and 72^d to engage behind the pawls respectively. Springs 71^e and 72^e connect the pawls with the controlling arms to provide for the drawing of either pawl into engagement with its ratchet through yielding connection which will permit the pawl to ride over the teeth of the ratchet wheel without rocking the rod 70^c.

The pawl-controlling arms above described carry studs 71^f and 72^f for coöperation with devices controlled by the ribbon. Thus the stud 71^f, located in rear of the rod 70^c (Fig. 7), is adapted to contact with a lip 73 on an arm 73^a journaled upon a stud 73^b which is secured in the left-hand frame piece. When the pawl 72 is operating upon the right-hand ratchet wheel 72^a and thus unwinding the ribbon from the left-hand spool and winding it on the right-hand spool, the stud 71^f clears the lip 73, but when the ribbon has been entirely unwound from the left-hand spool, said lip swings into the path of said stud so that when the rod 70^c next swings down, carrying the right-hand pawl back over the teeth of the right-hand ratchet, said stud will encounter said lip and thereby said rod 70^c will be rocked in a direction to draw the pawl 71 into engagement with its ratchet and withdraw the right-hand pawl 72 from engagement with the ratchet 72^a. It will be seen that the latter result ensues because the rod rocks in a direction to cause the lip 72^d to act against the rear edge of the pawl 72.

The stud 72^f on the right-hand pawl controller (Figs. 4, 6 and 9) is carried by a forwardly-projecting branch thereof and is adapted to coöperate with a laterally-turned lip 74 on an arm 74^a swung from a stud 74^b secured to the right-side frame

piece. When the ribbon is being unwound from the right-hand spool said stud 72^f clears the lip 74 but when the ribbon has been entirely unwound the said lip swings into the path of the stud so when the rod 70^c swings down, carrying the left-hand pawl back over the teeth of its ratchet, said stud 72^f encounters said lip and the arm 72^c is therefore swung back permitting the pawl 72 to engage its ratchet and at the same time withdrawing the pawl 71 from engagement with the left-hand ratchet by reason of the action of the lip 71^d against the rear edge of said pawl.

The rock rod 70^c and the controlling arms 80 secured thereto, and consequently the pawls controlled by said arms, are all held in the one position or the other against accidental displacement by detent arms 75 and 76 (Figs. 4, 6 and 7) pivoted respectively on 85 studs 75^a and 76^a secured to the arms 70^a of the bell crank levers. Springs 75^b and 76^b connect the upwardly extending portions of said detent arms with said bell crank arms to yieldingly swing the main 90 portions of the detent arms outwardly toward the pawl controllers. The latter carry studs 75^c and 76^c adapted to coöperate respectively with said detent arms, which are notched, as shown in 75^d and 76^d, for engagement with said studs respectively. Thus when the left-hand pawl 71 is disengaged from its ratchet wheel the stud 76^c is engaged with the notch 76^d and the controlling arm 71^c thus frictionally held 100 against accidental displacement. This arm being secured to the rock rod, the other controlling arm will likewise be held against accidental displacement. When said pawl 71 is engaged with its ratchet and the other 105 pawl 72 consequently disengaged, the stud 75^c of the right-hand controller is engaged with the notch 75^d and thus the rock rod and controlling arms are frictionally held against accidental displacement when this 110 reverse adjustment has been effected.

The arms 73^a and 74^a are connected respectively by springs 73^e and 74^e with other arms 73^d and 74^d loose upon the studs 73^b and 74^b their spring studs 73^f and 74^f projecting over shoulders of said arms 73^a and 74^a. The arms 73^d and 74^d carry rollers 73^g and 74^g adapted to run upon the ribbon *w* as it winds or unwinds from either spool, springs 73^h and 74^h pressing said rollers 120 against the ribbon. The latter at its opposite ends is attached to the spools and close to its ends carries curved metal plates 77 (Figs. 4 and 6) slotted for the threading through them of the ribbon (Fig. 5) and of 125 suitable dimensions to close segmental cavities 77^a in the spools. When the ribbon has fully unwound from either spool the plate will be lifted from the cavity as illustrated in Fig. 4 and this will permit the roller to 130

drop into the cavity thereby swinging the arm 73^a or 74^a, as the case may be, into position for causing a shifting of the pawl-controller associated therewith. The yielding connection between the roller-arms 73^a and 74^a and the abutment arms 73^a and 74^a provides for independent rise of the former as the ribbon roll enlarges (see Fig. 7) suitable stop studs 73^{''} and 73^{''} being provided to limit the swing of the arms 73^a and 74^a to that just sufficient to clear the studs 71¹ and 72¹. When the ribbon is entirely unwound from a spool the stud 73¹ or 74¹ as the case may be is in contact with the shoulder of the associated abutment arm (Fig. 6) and then of course downward swing of the roller arm as the roller enters the cavity causes outward swing of the abutment arm (Fig. 4).

As it is desirable, particularly in an adding and listing machine, to keep the ribbon taut, the spools are arranged to turn under friction and in the present instance the means employed for such purpose are utilized to hold the spools on the studs 70. The studs are turned to reduced diameter just back of their slotted heads, forming annular grooves, as shown in Fig. 3, and curved shoes 78 lie in these grooves to hold the spools on the studs and also supply the desired friction to oppose turning of the spools. Said spools are formed with or have secured to them disks 79 to confine the ribbon and the shoes 78 are formed as flanges on curved arms 78^a pivotally mounted upon the outer sides of said disks (Fig. 8). Springs 78^b connect the said arms with the disks and press the shoes against the bases of the annular grooves.

The arms 78^a have laterally turned portions at their outer ends to constitute handles or finger pieces by which to manipulate them, and it will be seen that by pressing against said finger pieces the arms can be swung on their pivots against the stress of their springs and the shoes lifted out of the grooves. Then the spools can be slipped off the studs.

It will be seen that the above-described construction provides for the reversal taking place without strain on the ribbon although under control thereof, for the disengagement of either pawl and accompanying engagement of the other pawl, always takes place during the retracting movement and so, when the ribbon is completely unwound, there is no chance for either pawl to be acting in an effort to further unwind it and thus impose a strain upon it. It will also be seen that the employment of the guard plates 77 insures proper co-action of parts in effecting the reversal for until the plate is lifted there can be no movement of the arm 73^a or 74^a, as the case may be, no matter how little ribbon is left on the spool, and then when the plate has lifted the arm gets

a definite movement to the base of the spool-cavity and the flange or lip 73 or 74, as the case may be, is drawn squarely into the path of the associated stud 71¹ or 72¹.

While as thus pointed out the construction here shown and described is well calculated to fulfil the objects primarily stated, yet it is to be understood that the invention is not limited to this particular construction but may be carried out in other ways.

What is claimed is:

1. In apparatus of the character described, the combination of ribbon spools and ratchets, pawls for alternately operating the latter, a reciprocating pawl-carrier, means movably mounted thereon for disengaging one pawl from its ratchet while engaging the other pawl with its ratchet, and means controlled by the ribbon for causing said pawl-shifting means to move relatively to the pawl-carrier through movement of the latter which retracts the active pawl.

2. In apparatus of the character described, the combination of ribbon spools and ratchets, pawls alternately operating the latter, a reciprocating pawl-carrier having a rock rod, pawl shifters secured to the latter, and means controlled by the ribbon for actuating said rod in retraction of the carrier.

3. In apparatus of the character described, the combination of ribbon spools and ratchets, pawls for alternately operating the latter, a reciprocating pawl-carrier having a rock rod on which the pawls are loosely mounted extending in opposite directions, arms secured to said rod and adapted to engage the pawls respectively to disengage them from the ratchets, springs connecting said arms with the pawls, and means controlled by the ribbon for actuating the rock rod through movement of the carrier which retracts the active pawl.

4. In apparatus of the character described, the combination of ribbon spools and ratchets, pawls for alternately operating the latter, a reciprocating pawl-carrier having a rock rod on which the pawls are loosely mounted extending in opposite directions, arms secured to said rod and adapted to engage the pawls respectively to disengage them from the ratchets, springs connecting said arms with the pawls, and movable ribbon-controlled abutment pieces for said arms respectively, either adapted upon exhaustion of ribbon from the associated spool to enter the path of the associated arm to cause actuation of the rock rod through movement of the pawl-carrier which retracts the active pawl.

5. In apparatus of the character described, the combination of ribbon spools and ratchets, pawls for alternately operating the latter, a reciprocating pawl-carrier having a rock rod on which the pawls are loosely mounted extending in opposite directions,

arms secured to said rod and adapted to engage the pawls respectively to disengage them from the ratchets, springs connecting said arms with the pawls, and swinging 5 abutment pieces for said arms respectively movable into and out of the paths of movement of said arms under control of the ribbon.

6. In apparatus of the character described, 10 the combination of ribbon spools and ratchets, pawls for alternately operating the latter, a reciprocating pawl-carrier having a rock rod on which the pawls are loosely mounted extending in opposite directions, 15 arms secured to said rod and adapted to engage the pawls respectively to disengage them from the ratchets, springs connecting said arms with the pawls, means controlled by the ribbon for actuating the rock rod 20 through movement of the carrier which retracts the active pawl, and detents for holding the rock rod in its two different positions.

7. In apparatus of the character described, 25 the combination of ribbon spools and ratchets, pawls for alternately operating the latter, a reciprocating pawl-carrier having a rock rod on which the pawls are loosely mounted extending in opposite directions, 30 arms secured to said rod and adapted to engage the pawls respectively to disengage them from the ratchets, springs connecting said arms with the pawls, movable ribbon-controlled abutment pieces for said 35 arms respectively, each adapted upon exhaustion of ribbon from the associated spool to enter the path of the associated arm to cause actuation of the rock rod through movement of the pawl-carrier which retracts the active pawl, and detents for the 40 arms respectively to hold the same and the rock rod in the two different positions.

8. In apparatus of the character described, 45 the combination of ribbon spools and ratchets, pawls for alternately operating the latter, a reciprocating pawl-carrier having a rock rod on which the pawls are loosely mounted extending in opposite directions, arms secured to said rod and 50 adapted to engage the pawls respectively to disengage them from the ratchets, springs connecting said arms with the pawls, movable ribbon-controlled abutment pieces for said arms respectively, each adapted upon 55 exhaustion of ribbon from the associated spool to enter the path of the associated arm to cause actuation of the rock rod through movement of the pawl-carrier which retracts the active pawl, and pivoted spring-drawn 60 detent arms for engaging the pawl-controlling arms respectively.

9. In apparatus of the character described, 65 the combination of ribbon spools with peripheral cavities, a ribbon attached at opposite ends to said spools and carrying

rigid closures for said cavities, alternately operable means for turning the spools step by step, and controlling devices for said means comprising members adapted to enter the spool cavities.

10. In apparatus of the character described, 70 the combination of ribbon spools with peripheral cavities, a ribbon attached at opposite ends to said spools and carrying rigid closures for said cavities, alternately operable means for turning the spools step by step, and controlling devices for said means comprising pivoted arms yieldingly impelled toward the spools and adapted to enter the cavities thereof.

11. In apparatus of the character described, 75 the combination of ribbon spools with peripheral cavities, a ribbon attached at opposite ends to said spools and carrying rigid closures for said cavities, alternately operable means for turning the spools step by step, and controlling devices for said means comprising pivoted arms yieldingly impelled toward the spools and adapted to 80 enter the cavities thereof, swinging abutment arms adapted to be acted upon by said pivoted arms, ratchets for the spools, pawls engageable with and disengageable from said ratchets respectively, an oscillating pawl-carrier, and pawl-controllers on said carrier coöperating with said abutment arms.

12. In apparatus of the character described, 85 the combination of ribbon spools with peripheral cavities, a ribbon attached at opposite ends to said spools and carrying rigid closures for said cavities, alternately operable means for turning the spools step by step, and controlling devices for said means comprising pivoted arms yieldingly impelled toward the spools and adapted to enter the cavities thereof, swinging abutment arms adapted to be acted upon by said pivoted arms, springs connecting the latter with the abutment arms, ratchets for the 90 spools, pawls engageable with and disengageable from said ratchets respectively, an oscillating pawl-carrier, and pawl-controllers on said carrier coöperating with said abutment arms.

13. In apparatus of the character described, 95 the combination of ribbon spools with peripheral cavities, a ribbon attached at opposite ends to said spools and carrying rigid closures for said cavities, alternately operable means for turning the spools step by step, and controlling devices for said means comprising pivoted arms yieldingly impelled toward the spools and adapted to enter the cavities thereof, swinging abutment arms adapted to be acted upon by said pivoted arms, ratchets for the spools, pawls engageable with and disengageable from said ratchets respectively, a reciprocating pawl-carrier having a rock rod on which the 100

pawls are loosely mounted, and arms secured to said rock rod and adapted to disengage the pawls respectively from their ratchets, said arms coöoperating with the abutment 5 arms for such purpose.

14. In apparatus of the character described, the combination of ribbon spools and ratchets, pawl-carrying levers and pawls, duplex means for reciprocating the 10 pawl-carrying levers, a rock shaft carried by the latter, means on the rock shaft for engaging the pawls with and disengaging them from the ratchets, and ribbon-controlled devices for actuating the rock shaft.

15. In apparatus of the character de- 15 scribed, the combination of a spool journal stud having a reduced portion, a spool, and a spring-held arm on said spool and engag- ing the reduced portion of the stud.

16. In apparatus of the character de- 20 scribed, the combination of a spool journal stud having a reduced portion, a spool, and a spring-held pivoted arm having a shoe occupying the reduced portion of the stud.
